UNITED STATES PATENT OFFICE.

ALBERT J. DOTY, OF PHILADELPHIA, PENNSYLVANIA, ASSIGNOR TO THE GOODWIN GAS STOVE AND METER COMPANY, OF SAME PLACE.

DESIGN FOR A GAS-STOVE.

SPECIFICATION forming part of Design No. 18,007, dated January 10, 1888.

Application filed October 14, 1887. Serial No. 252,403. Term of patent 14 years.

To all whom it may concern:

Be it known that I, ALBERT J. DOTY, a citizen of the United States, residing in the city of Philadelphia, in the State of Pennsylvania, have invented and produced a certain new and original Design for Gas-Stoves, of which the following is a full, clear, and exact description, reference being had to the accompanying drawing, forming a part of this specification.

My invention relates to stoves in which gas is burned for heating purposes; and it consists of the novel form of the top and of the front of the stove and of the ornamentation on the two sides thereof, which are at right angles with the open front.

It is fully illustrated in the drawing, which is an elevation showing both the top and front of the stove and also one of the ornamented sides thereof.

The leading features of my design consist in the form or configuration of the two sides B B, wider at the base than at the top, curving inwardly, as at b¹, about two-thirds of the height, and thence outwardly almost a complete semicircle, as at b², joining a flat top, b², at the outer extremity of the side. The intermediate rounded projection, b, may or may not be added, as desired. This form of the sides B B is combined with a top, A, of the form to correspond, and in consequence is flat at the rear and rounded to almost a full circular form at the front. The ornamentation of the sides B B consists, essentially, of the outside band, K, of a vine-like continuous figure of alternating reversed curves having a rosette-like leaf springing from the bifurcated top of each curve, as shown, extending all around the outer edge, and of the central typical figure, F,

of the sun. Rosettes C are added to fill in the corners and projecting parts, and ornamental lines D and G above and below the figure F, to fill up the otherwise blank spaces on the surface, while the feet of the stove, H H, are ornamented as shown.

Having thus described my invention, I claim—

1. The design for the form and ornamentation of a gas stove, consisting of the sides B B, having an inwardly-curved front, b¹, an outwardly-projecting rounded top, b², flattened at the rear b², with a top, A, flat at the rear and rounded at the front to correspond with the curvature of the top of said sides B B, each of the latter being ornamented with the typical sun figure F, substantially as shown and described.

2. In a design for a gas-stove, the external sides B B of the body, having the ornamental band K, consisting of a vine-like continuous figure of alternating reversed curves having a rosette-like leaf springing from the bifurcated top of each curve, extending around the outer edge of said sides, and following the curvatures thereof, substantially as shown and described.

3. In a design for a gas-stove, the band K, as shown, extending around the outer edge of the external surface of the sides B B, and the typical sun figure F with said band, substantially as shown and described.

In testimony whereof I have hereunto affixed my signature this 4th day of October, A. D. 1887.

ALBERT J. DOTY.
